CLAIM

The ornamental design for a head mount display, as shown and described.

DESCRIPTION

FIG. 1 is a front perspective view of a head mount display showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear perspective view thereof; and,

FIG. 9 is a reference view thereof showing an example of the usage of the subject design in which the user wears the subject design.

The broken lines depict portions of the head mount display that form no part of the claimed design.
